CLAIM

We claim the ornamental design for a two-cell beverage box, as shown and described.

DESCRIPTION

FIG. 1 is a top perspective view of a two-cell beverage box showing the claimed design with a telescoping portion positioned in an extended configuration.

FIG. 2 is a front elevation view thereof.

FIG. 3 is a rear elevation view thereof.

FIG. 4 is a left-side elevation view thereof.

FIG. 5 is a right-side elevation view thereof.

FIG. 6 is a top plan view thereof.

FIG. 7 is a bottom plan view thereof.

FIG. 8 is a plan view of the two-cell beverage box shown in a fully collapsed configuration.

FIG. 9 is a rear elevation view of the two-cell beverage box shown in a partially collapsed configuration.

FIG. 10 is a front elevation view thereof.

FIG. 11 is a front perspective view of the two-cell beverage box shown with the telescoping portion positioned in a retracted configuration; and,

FIG. 12 is a side top perspective view thereof.

Those features shown in broken lines, such as the broken lines denoting lines of weakness shown in FIGS. 2-5 and 8-12, form no part of the claimed design.
